UNITED STATES PATENT OFFICE.

ALFRED I. DU PONT, OF WILMINGTON, DELAWARE, AND HIRAM R. HARDING, OF BALTIMORE, MARYLAND, ASSIGNEES TO CLEAN FOOD PACKING MACHINE COMPANY, OF WILMINGTON, DELAWARE, A CORPORATION OF DELAWARE.

SCALDING APPARATUS FOR TOMATO-PEELING MACHINES.

Application filed January 25, 1922. Serial No. 531,740.

To all whom it may concern:

Be it known that we, ALFRED I. DU PONT, residing at Wilmington, county of New Castle, State of Delaware, and HIRAM R. HARDING, residing at Baltimore, State of Maryland, citizens of the United States, have invented certain new and useful Improvements in Scalding Apparatus for Tomato-Peeling Machines, of which the following is a specification.

Our invention relates to an apparatus for scalding fruits and vegetables preparatory to the skinning operation and is especially adapted for machines which skin, slice and core tomatoes by a continuous operation of the type covered by U. S. Patent No. 1,423,421 dated July 18, 1922.

The object of the present invention is to increase the efficiency of the scalding operation, to conserve the heat supply and to apply the steam more effectively to the individual tomatoes. Our invention will be understood from the following description in connection with the accompanying drawings, in which—

Figures 1 and 1^a illustrate in longitudinal section a complete tomato peeling machine embodying our present improved scalding apparatus designated by the letter B, and also the initial washing scalding and feeding apparatus A and skinning and coring apparatus C;

Figures 2 and 2^a are enlarged views, which taken together illustrate the scalding apparatus in longitudinal section—

Figures 3 and 3^a are top plan views of Figs. 2 and 2^a respectively—

And Figure 4 is a transverse sectional view on the line 4—4 of Fig. 1^a.

The entire machine is adapted to carry on the several operations in continuous succession. The fruit is carried from one apparatus to the next by the endless conveyor 2, which passes over the drums 3 and 4 at either end.

The apparatus A for initially washing, heating or partially scalding and automatically placing the tomatoes stems upward upon the meshes of the conveyor belt in alignment in a series of parallel rows is described and claimed in our co-pending application Serial No. 531,498 filed January 24, 1922. The tomatoes or other fruit are thus conveyed in an orderly manner into the steam scalding apparatus B. This appara-

tus is encased in a housing or hood of sheet metal plates suitably supported and braced by angle iron frame members 10, the whole being carried by the uprights or standards 12 of the machine frame. The bottom, sides and top are lagged with sheets of asbestos to retain the heat. The top plates are separately bolted so that they may be readily removed when it is desired to secure access to the interior of the scalding apparatus. The end plates 15 and 16 are spaced slightly apart to permit the passage of the conveyor belt and the fruit carried thereon. Steam exhaust vents or stacks 17, 17' are inserted in the top plates at intermediate points at equal distances from the ends. The steam supply pipe 20 connects centrally with two manifolds 23, 24 extending longitudinally within the housing upon opposite sides and respectively above and below the conveyor belt. A series of horizontal distributing jet or spraying pipes 25 and 26 extend across the housing from these manifolds, the corresponding upper and lower pipes of each set being in vertical alignment and provided with oppositely disposed openings so that a jet of steam is projected simultaneously upon each tomato from above and below. The outer ends of the branch pipes 25 and 26 preferably extend through the wall of the housing and are capped.

The steam is supplied to the manifolds at say 50 lbs. pressure, but by reason of the large number of jet openings there is substantially no steam pressure in the housing.

For the purpose of causing the steam within the housing to move in opposite directions toward the exhaust stacks 17, 17', we produce a fluid injector action at each end of the housing. Directly in front of the entrance opening and outside of the housing a pipe 30 supplies steam to transverse pipes 31 and 32 arranged above and below the conveyor belt and provided with obliquely arranged openings which project steam jets at converging angles into the entrance opening of the housing. This results in an injector action, drawing air inwardly in the direction of the moving belt and producing currents in the steam or vapor within the housing directed toward the exhaust stack 17. By using steam as the injector medium at the entrance end, the tomatoes which have been previously heated are not chilled.

At the discharge end of the scalder a pipe 36 supplies water to a pair of pipes 37, 38 located outside of the housing and which are provided with apertures which direct jets 5 of water converging at the discharge opening. These converging jets of water also produce an injector action to draw in air and direct it inwardly along with the mist or fine spray which induces currents in the 10 steam or vapor in the direction of the steam exhaust stack 17'. The steam or vapor within the housing is thus constantly discharged through the exhaust stacks and none of it escapes through the end openings. In addition 15 to the chilling action produced by the sprays from the pipes 37 and 38 we further chill the tomatoes by oppositely directed water jets from pipes 39 and 40 which are also supplied from the pipe 36. As is well known, the pulp and skins of the tomatoes 20 are expanded while they are subjected to the intense heat of the steam bath in passing through the scalder and when they are then subjected to the chilling action of the cold 25 water jets, the pulp or meat is contracted, thereby loosening the skins. The tomatoes are thus brought into proper condition for the slicing, skinning and coring operation to which they are next subjected in the apparatus C as they are carried along on the 30 conveyor belt.

We claim:—

1. A scalding apparatus for fruit and vegetable peeling machines, comprising a 35 housing provided with entrance and exit

openings in the end walls and exhaust vents in its top wall, a conveyor belt movable therethrough, steam supply manifolds located within the housing upon either side thereof and positioned respectively above and below the conveyor, branch pipes extending from the manifolds transversely across the chamber of the housing, said pipes being arranged in vertically alined pairs above and below the conveyor and having 40 openings to direct steam jets upon the fruit in transit, and current creating means at said entrance and exit openings to cause the steam to flow inwardly from said openings 45 toward said exhaust vents.

2. In apparatus as set forth in claim 1, means external to the housing for producing a fluid injector action at the mouth of the entrance and exit openings to thereby cause the steam or vapor within the housing 50 to flow toward the exhaust vents.

3. In apparatus as set forth in claim 1, means for causing the steam or vapor within the housing to move inwardly from the end 55 openings toward the exhaust vents, comprising pairs of pipes located exteriorly at each end of the housing and provided with jet openings adapted to project converging sprays of steam and water into the entrance and exit openings respectively.

In testimony whereof we affix our signatures.

ALFRED I. DU PONT.
HIRAM R. HARDING.
